SAFETY CAN

Rudolph J. Anschicks, Chicago, Ill., assignor to
Protectoseal Company of America, Inc., Chi-
cago, Ill., a corporation of Illinois

Application December 18, 1937, Serial No. 180,600

9 Claims. (Cl. 221—15)

The invention relates to liquid containers and more particularly it relates to cans and receptacles such as are commonly used for holding kerosene, gasoline, naphtha, and other combustible and explosive liquids.

5 The invention has among its objects the provision of improvements in closure devices adapted to effectively seal spouts or conduits for such receptacles.

10 Another object of the invention is the provision of improved means adapted to be manually manipulated to move the device to open position and to automatically return and maintain the device in closed position.

15 Many other objects and advantages of the construction herein shown and described will be obvious to those skilled in the art from the disclosure herein given.

To this end the invention consists in the novel 20 construction, arrangement, and combination of parts herein shown and described and more particularly pointed out in the appended claims.

25 Referring now to the drawing wherein like reference characters indicate like or corresponding parts:

Fig. 1 is an elevational view of the top portion of a can equipped with the devices embodying the invention;

Fig. 2 is a view along the line 2—2 of Fig. 1;

30 Fig. 3 is a view along the line 3—3 of Fig. 2; and Fig. 4 is a view along the line 4—4 of Fig. 1.

Referring now more particularly to the drawing the numeral 10 generally designates a can equipped with a device embodying the principles 35 of the invention and having a carrying handle 11 consisting of a bar of malleable iron or other suitable material fastened by rivets, welding or the like to the top of the can. The handle 11 provides vertical members 11a and 11b connected 40 at their upper ends.

A spout 12, positioned adjacent to and preferably in diametrical alignment with the handle 11, is fastened to the can by welding, soldering or the like to provide a sealed connection. The supply of liquid may be replenished by delivery into the spout 12 or may be delivered through an intake conduit not shown. A screen 13, enclosing the inner end of the spout 12, provides a strainer preventing foreign particles from reaching the 45 liquid contents of the can through the spout and retaining within the can such foreign particles as may be in the liquid.

The closure device is mounted on the discharge end of the spout 12 in a manner to effectively 50 seal the spout against leakage should the can be

accidentally overturned or submitted to the usual underwriter's tests. The closure device comprises a disc or cap 14 of metal or other suitable rigid material and having a diameter somewhat larger than that of the open end of the spout. 5 The cap 14 is provided with an annular flange 15 within which is positioned a disc 16 consisting of medium hard rubber or fibrous material having similar cushioning qualities. The disc 16 is fastened to the cap 14 by a screw bolt 9 or by any 10 other suitable means such as a layer of adhesive material and is adapted to over-lap completely and seal the open end of the spout.

The cap 14 is connected with the spout 12 and revolvable from closed to open position and vice 15 versa by means of an L-shaped lever 17, having one end bifurcated, and positioned between a pair of spaced apart projections 18 formed with the spout. The projections 18 are integrally formed on the side of the spout adjacent the handle section 11a and provide a mounting for a pin 19 extending through the bifurcated end portions of the lever 17. The other end of the lever 17 extends over the cap 14 and provides a socket 20 preferably concentric with the can. A stem 20 member 21, preferably rigidly connected with the cap 14, extends into and loosely fits the socket 20. The stem member 21 is fastened to the lever 17 by a pin 22 extending transversely through the socket 20 and through a diametrical hole 23 provided in the stem member. The hole 23 has a diameter substantially greater than the diameter of the pin 22 to permit limited longitudinal and lateral movement of the stem member 21 in the socket 20. The closed end of the socket 20 is 35 convergent and preferably concave or substantially hemispherical. The adjacent end of the stem member 21 is also convergent and preferably convexly curved to permit of its oscillation within the socket 20. The pin 22 is so positioned 40 in the hole 23 as to permit the convergent end of the stem member 21 to contact with the innermost extremity of the closed end of the socket 20 and thereby to operate as a universal joint when the lever is pressed toward the cap 14. 45

The lever 17 is normally pressed toward the cap 14 by means of a relatively rigid wire 24 forming a coil spring mounted on the pin 19 between the bifurcated end portions of the lever. The ends of the wire 24 extend laterally and oppositely to 50 respectively engage the lever 17 and the spout 12, the coil being so mounted that its resilience constantly tends to move the socket end of the lever toward the cap 14. The substantial point contact of the stem member 21 with the lever 17 at the 55

convergent inner end of the socket 20 permits the cap 14 to be self-adjusting and to be seated with the cushion disc 16 in uniform contact with the open end of spouts having different angles of inclination to the axis of the spout. The automatic adjustment of the cap 14 also results in the pressure by the lever 17 being uniformly distributed over that portion of the cushion disc 16 in direct contact with the end face of the spout 10 and thereby seals the spout regardless of irregularities in its end face.

The cap 14 is adapted to be moved to open the spout 12 against the resistance of the coil spring 24, this being accomplished by manual actuation 15 of a pull lever 25. The lever 25 is connected by a pin 26 with the upper ends of the bifurcated portions of the lever 17. The lever 25 extends through a slot 27 formed in the adjacent portion 11a of the carrying handle 11 and terminates in 20 a handle member 28 positioned between the portions 11a and 11b of the carrying handle and in spaced relation to the vertical portion 11b of the carrying handle. The handle member 28 is so positioned relative to the member 11b that 25 both may be simultaneously grasped with one hand, with the lever 25 lifted into substantial perpendicularity to the bifurcated end of the lever 17. In this position of the handle member 28 the operator, by closing his hand, is enabled 30 to exert a pull on the lever 25 which rotates the lever 17 and the cap 14 to open the spout 12. Upon release of the handle member 28, the spring 24 snaps the cover 14 back to closed position of the spout 12. The described manual manipulation 35 of the levers 25 and 17 to open the spout may be accomplished in any position of the can. In practice, the can is preferably tilted to a position wherein the spout 12 is suitably inclined to discharge into the receiving aperture of a vessel 40 to be filled, the tilting being done with the spout closed. The spout is then opened, by manual manipulation of the levers 25 and 17 as described, without further movement of the can or shifting of his hand by the operator. The location of the lever 25 and handle member 28 is such that the 45 spout can not be accidentally opened, and if the can should be overturned either inadvertently or for the purpose of subjecting it to underwriters' tests, there is no possibility of leakage through the spout 12.

Thus, it will be seen that I have provided simple and inexpensive improvements in closure devices of the kind described whereby the devices are adapted to be seated on spouts having their open 55 ends inclined at any suitable angles to the vertical axes of cans on which they are mounted and uniform pressure is exerted by the cushioned closure devices over the end face of the spout adapted to effectively seal the spouts regardless 60 of any irregularities in their end faces or the particular angle of inclination of such faces to the vertical axes of the cans.

Having thus described my invention, it is obvious 65 that various immaterial modifications may be made in the same without departing from the spirit of my invention; hence I do not wish to be understood as limiting myself to the exact form, construction, arrangement and combination of parts herein shown and described or uses 70 mentioned.

What I claim as new and desire to secure by Letters Patent is:

1. A closure device for the discharge conduit of a receptacle, said device comprising a disc having one face adapted to be seated on and to seal the

discharge end of the conduit, a spring pressed lever mounted on the receptacle, and means providing a loose ball and socket joint connection of the disc with the lever, said means being operable by the lever pressure to engage the disc with the end of the conduit and then to selectively tilt the disc in any direction requisite to bring it into exact parallelism with the bounding end face of the conduit. 5

2. A closure device for the discharge conduit of 10 a receptacle, said device comprising a disc having one face adapted to be seated on and to seal the discharge end of the conduit, a spring pressed lever mounted on the receptacle, means providing a loose ball and socket joint connection of the 15 disc with the lever, said means being operable by the lever pressure to engage the disc with the end of the conduit and then to selectively tilt the disc in any direction requisite to bring it into exact 20 parallelism with the bounding end face of the conduit, and means operable to move the lever and disc away from the conduit.

3. A closure device for the discharge conduit of a receptacle, said device comprising a disc having one face adapted to be seated on and to seal the 25 discharge end of the conduit, a lever mounted on the receptacle having one end providing a socket adjacent the conduit, a stem member connected at one end with the disc and having its other end projecting into the socket, the extreme end of 30 said projecting portion being convergent and adapted to bear against the lever at the closed end of the socket, means adapted to retain the stem member in the socket and to permit its oscillation about its convergent end as a pivot, and 35 resilient means tending to move the lever to seat the disc on the discharge end of the conduit.

4. A closure device for the discharge conduit of a receptacle, said device comprising a disc having one face adapted to be seated on and to seal 40 the discharge end of the conduit, a lever mounted on the receptacle having one end providing a socket adjacent the conduit, a stem member connected at one end with the disc and having its other end projecting into the socket, the extreme 45 end of the projecting portion of the stem member being convergent and adapted to bear against the lever at the bottom of the socket, means adapted to retain the stem member in the socket and permit its oscillation about its convergent 50 end as a pivot, resilient means tending to move the lever to seat the disc on the discharge end of the conduit, and means manually operable to move the lever and disc away from the conduit.

5. A closure device for the discharge conduit 55 of a receptacle, said device comprising a disc having one face adapted to be seated on and to seal the discharge end of the conduit, a lever mounted on the receptacle and providing a socket adjacent the conduit, a stem member rigidly connected at one end with the disc and having its other end projecting into the socket, the cross-sectional 60 dimensions of the socket being substantially greater than the corresponding cross-sectional dimensions of the stem member, the inner ends of the socket and the stem member being 65 respectively concave and convergent and adapted for bearing contact, means fastening the stem member to the lever, said means being adapted to permit limited longitudinal movement and 70 oscillation of the stem member in the socket, and resilient means tending to move the lever to seat the disc on the discharge end of the conduit.

6. A closure device for the discharge conduit of a receptacle, said device comprising a disc hav- 75

- ing one face adapted to be seated on and to seal the discharge end of the conduit, a lever mounted on the receptacle and providing a socket adjacent the conduit, a stem member rigidly connected at one end with the disc and having its other end projecting into the socket, the cross-sectional dimensions of the socket being substantially greater than the corresponding cross-sectional dimensions of the stem member, the inner ends of the socket and the stem member being respectively concave and convergent and adapted for bearing contact, means fastening the stem member to the lever, said means being adapted to permit limited longitudinal movement and oscillation of the stem member in the socket, and resilient means adapted to move the lever to seat the disc on the discharge end of the conduit, and means manually operable to rotate the lever and move the disc from its seat.
- 5 7. The combination with a can having a discharge spout and a carrying handle in juxtaposition, of a closure device for the spout comprising a disc having one face adapted to be seated on and to seal the discharge end of the spout, a lever having one end providing a socket and its other end pivotally connected with the can adjacent the handle, a stem member having one end rigidly connected with the disc and its other end projecting into said socket, the cross-sectional dimensions of the socket member being greater than the corresponding cross-sectional dimensions of the stem member, the inner end of the socket 10 being concave and the inner end of the stem member being convergent and adapted for bearing contact with said concave end of the socket, means fastening the stem to the lever, said means being adapted to permit limited longitudinal 15 movement and lateral oscillation in all directions of the stem member relative to the lever, resilient means tending to move the lever to seat the disc on the discharge end of the spout, and a member manually operable by a pull exerted thereon 20 to rotate the lever to move the disc away from the spout, said member and handle being contiguous and both adapted to be grasped by one hand of the operator to exert a pull on said member.
- 25 9. In a receptacle of the kind described and in combination, a discharge conduit, a closure member adapted to be seated on and seal the discharge end of said conduit, a spring pressed lever movable in a plane coinciding with the longitudinal axis of the conduit, means connecting said closure member and lever whereby the lever normally maintains the closure member in conduit sealing position, and means operable to retract the lever in opposition to the spring pressure and thereby to unseat the closure member, said connecting means being adapted to permit limited relative movement of the closure member away from and towards the lever when the lever is retracted, said connecting means being operable by return movement of the lever to act as a ball and socket joint tending to tilt and uniformly press the closure member against the discharge end of a conduit bounded by a face transversely inclined to the plane in which said lever 30 is movable.
- 30 40 45
- 35 8. The combination with a can having a discharge spout and a handle in juxtaposition, of a closure device for the spout comprising a disc

RUDOLPH J. ANSCHICKS.
